UNITED STATES PATENT OFFICE

HERMAN HANSEN, OF NEW YORK, N. Y., ASSIGNOR TO FRANCIS KEIL & SON, INC., A CORPORATION OF NEW YORK

ATTACHMENT FOR DOORS

Application filed April 3, 1928. Serial No. 266,983.

This invention relates to attachment for doors and more particularly to a device for permitting the occupant of a room, apartment, or the like, to view, with safety, and to communicate with, if desired, persons seeking admission.

One of the objects of this invention is to provide a device of the above-mentioned character that will be of simple construction,

- 10 thoroughly dependable action and capable of ready attachment to a door. Another object is to provide a device of the above-mentioned character which will be of simple and highly convenient manipulation when in use 15 and embodying features of construction whereby safety to the occupant of the room, apartment, or the like, may be assured in a thoroughly dependable and practical manner. Another object is to provide a device of the 20 above-mentioned character that will be of inexpensive construction and capable of inexpensive manufacture on a large scale. Another object is to provide a device of the above-mentioned character in which complication 25 of construction is avoided and thus great convenience in use, as well as reliability of action, is achieved. Another object is to provide a device of the above-mentioned character that will be of compact construction 30 and of unobtrusive appearance. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

- 40 In the accompanying drawings in which is shown a preferred embodiment of my invention,

Figure 1 is a front view of the device as seen from the outside of a door, the door being 45 only fragmentarily shown;

Figure 2 is a view as seen from the rear of Figure 1 and shows the device as seen from the inside of the door;

- Figure 3 is a vertical sectional view along 50 the line 3—3 of Figure 2;

Figure 4 is a view as seen from the left of Figure 2, certain parts of the device being shown in partially opened relation;

Figures 5, 6 and 7 are plan views respectively of three different parts of the device; 55

Figure 8 is a sectional view as seen on the line 8—8 of Figure 6, and

Figure 9 is a sectional view along the line 9—9 of Figure 7.

Similar reference characters refer to similar parts throughout the several views in the drawings.

Referring now to the drawing and more particularly to Figures 1, 2 and 3, a portion of the door is indicated at 10 and it is provided with an opening indicated at 11 preferably circular; a ring-like frame member generally indicated at 12 and preferably of substantially T-shaped cross section (see Figure 3) is made up of a plate-like member 13 adapted to rest flatwise against the door or door panel and a ring-like flange 14 which preferably snugly fits and projects through the opening 11. The plate-like member 13 and the ring member 14 are preferably integral and may be cast, for example, in one piece, and it will be noted from Figure 3 that the plate member 13 projects to either side of the ring member 14. The plate member 13 is preferably extended to provide a suitable number of ears 15 (Figure 1) through which suitable securing means such as the bolt 16 may be passed to fasten the frame member 12 to the door or door panel. 70 75

The plate member 13 is provided with an opening 17 preferably circular and this opening is provided with a suitable grating indicated at 18, the members or bars forming the grating 18 being preferably integrally formed with the frame member 12. 80 85

At its right-hand end, as seen in Figures 2 and 5, the frame member is provided with two spaced upstanding lugs or ears 19—20 which preferably fall within the compass of the ring member 14; the member 14 is cut away as at 21 and 22 (see Figure 5). At its left-hand side, as viewed in Figures 2 and 5, and as is better shown in Figure 4, the member 14 is provided with an upstanding keeper 23 shaped substantially as shown in Figure 100

4. To the right of the keeper 23 the ring member is cut away as at 24 (see Figure 5).

A ring-like frame member 25 of L-shaped cross-section (see Figure 3) is adapted to be somewhat snugly received within the ring member 14 of the frame 12 and to rest against the plate member 13. The frame member 25 has mounted therein as by appropriate rivets 26 (see Figure 6) a non-breakable glass generally indicated at 27. The glass 27 is preferably made up of two separate sheets 28 and 29 of glass between which is a sheet of celluloid 30 suitably connected to each glass and preferably bonded thereto.

15 At its right-hand portion, as seen in Figure 6, the frame member 25 is provided with a pair of lugs 31 and 32 projecting away from the frame 25 and spaced and shaped so that their right-hand ends fit substantially into the slots 21 and 22 cut into the ring member 14, the lugs 31 and 32 being substantially alined with the lugs 19 and 20 respectively.

20 The left-hand portion of the frame member 25 (as seen in Figure 6) is provided with a rectangularly shaped projection 33 adapted to fit into the recess 24 (Figure 5) in the ring member 14 of the frame 12 and upon this portion of the frame 25 is mounted a latch generally indicated at 34 adapted to coact with the keeper 23.

25 The latch 34, shown in cross-section in Figure 8 on an enlarged scale, comprises preferably a hollow cylindrical member 35 pivotally mounted and secured to the frame 25, as is generally indicated at 36. The upper portion of the cylindrical member 35 is shaped to form a knob, as at 37, and is preferably knurled to permit ease of manual manipulation.

30 Near the lower portion of the cylindrical member 35 there is integrally formed therewith a projecting lug 38 adapted to form a latch for coaction with the keeper 23 on the frame 12. Housed within the cylindrical member 35 and supported thereby is a helical spring 39 having its upper end anchored in the member 35 as by being passed into a small opening 40 provided therein. The lower end of the spring 39 is anchored to the frame member 25 as by passing the lower end into a suitable aperture 41 provided in the member 25, and through a slot in member 35.

35 As is shown in Figure 6, the cylindrical member 35 of the latch 34 is provided with a lug 42 projecting radially therefrom near its lower end (see also Figure 4) and in the frame member 25 is secured an upstanding pin 43 positioned in the path of rotary movement of the lug 42 about the axis of the member 35.

40 The spring 39 is tensioned so as to tend to rotate the latch 34 and hence the lug 38 in clockwise direction, as seen in Figure 6, the pin or stop 43 on the frame 25, coacting with the lug 42, acting to limit the extent of

this rotary movement and to hold the lug 38 in substantially the position shown in Figure 6.

45 The frame member 25 is preferably of somewhat less thickness than the ring member 14, as viewed in Figure 3, and shaped to fit into the ring member 14 but to overlap its right-hand face is a small closure or door 44 preferably made of metal. The door 44 is of a generally circular shape and is provided at its right-hand portion, as seen in Figures 2 and 7, with a pair of upstanding lugs or ears 45 and 46 so spaced that they are alined with and received between the lugs 31 and 32 of the frame member 25, the latter lugs being in turn alined with and received between the lugs 19 and 20 of the frame 12. Through suitable alined openings in all of these alined lugs is passed a hinge pin 47 whereby the window frame 25 and the door 44 are coaxially hinged to the frame 12.

50 The door 44 is cut away as at 48 at its left-hand portion, as seen in Figure 7 (see also Figures 2 and 4) so that the door 44 clears the latch construction 34. A knob 49 preferably knurled is secured to the door 44 to permit manual manipulation thereof.

55 About the hinge pin 47 and extending therealong and between the lugs or ears 45 and 46 is a helical spring 50 having one of its ends extended to engage the ring member 14 of the frame 12 and having its other end extended toward the center portion of the door 44 and resting thereagainst. The spring 50 is tensioned so as to rotate the door 44 in a direction to cause the door to close.

60 Preferably, the knob 49 is constructed to coact with a latching mechanism for locking the door 44 in closed position. This latching mechanism may conveniently take the form shown in cross-section on an enlarged scale in Figure 9, it being noted that the door 44, near its left-hand portion as seen in Figures 2 or 7, is provided with a substantially cylindrical housing 51 preferably cast integrally with the door 44 and extending in a direction toward the cut away portion 48. The housing 51 is open-ended at its left-hand end and has slidably mounted therein a latch member 52, urged in a direction outwardly through the open end by a spring 53.

65 The housing 51 has a lengthwise extending slot 54 through which passes the shank of the knob 49 so that the shank may be secured to the latch member 52. Thus, the latch 52 may be manually moved against the action of the spring 53.

70 The outer end of the latch 52 overlaps the cut away portion 48 of the door 44 and is adapted to coact with a suitable keeper, the latter being conveniently formed upon the lower portion of the cylindrical member 35 of the latch 34 and conveniently taking the form of a bevelled flange 55 extending pe-

ipherally sufficiently about the member 35 so that a portion of the flange 55 is always presented for coaction with the latch 52 even though the member 34 be manually rotated.

5 The keeper 52 is adapted to snap into position underneath the flange keeper 55, thus to lock the door 45 to the window casing frame 25. It is to be understood, however, that many features of my invention may be 10 achieved in practice without actually locking or latching the door 45 and that such features and advantages may be achieved by simply mounting the knob 49 directly upon the door 44.

15 Considering now the operation and use of this device, it is first to be noted that should occasion arise for the occupant of the room, apartment or house to see who is seeking admittance, the occupant first takes hold of 20 the knob 49, moves the latter to disengage the latch 52, and opens the door 44 against the tension of the spring 50, the window frame 25 with the non-breakable glass 27 therein being held in secure closed and locked 25 position by the interengagement of the lug 38 of the latch 34 with the keeper 23. There is thus afforded a clear view through the door, but while such a view is being taken the occupant is in entire safety and under appropriate protection.

30 In the first place, the gratings 18 restrict the opening 17 so as to prevent any implement of substantial size from being passed therethrough while the non-breakable glass 35 27 prevents injury to the eye of the observer. Thus, even though the glass 27 might be cracked as by receiving a blow from the exterior, it will not shatter and scatter and thus the eye of the observer is fully protected.

40 Furthermore, the eye of the observer is protected against drafts. Also, the glass prevents any substance to be thrown through the opening.

Should the observer or occupant desire to 45 communicate with the caller either by word of mouth or to receive from the caller papers or the like, the observer lets go of the door 44 by releasing the knob 49 and takes hold of the latch 34, operates the latter to disengage 50 the lug 38 from the catch 23, and swings the window and its frame 25 open, thus carrying into open position also the door 44.

Through the openings intervening the gratings 18 conversation may be carried on or 55 papers and the like passed through. Releasing the latch 34 brings the spring 50 into action which causes the prompt closing movement of the window and its frame 25, as well as of the door 44, the spring 50 having caused 60 a latching of the door 44 to the member 35, when the door 44 was previously released. The parts are restored by the spring 50 into the position shown in Figures 2, 3 and 9. The lug 38 on the latch 34 snaps in behind the 65 keeper 23, due to the yielding action of the

spring 39, and the shape of the keeper 23, all as will be clear from Figures 4 and 8, and without permitting disengagement of the latch 52 from the keeper 23, whereupon the window frame 25 with its non-breakable glass 70 and door 44 are locked in closed position and the parts are in readiness for subsequent actuation.

It will thus be seen that there has been provided in this invention, a device in which 75 the several objects above-mentioned, as well as many thoroughly practical advantages, are successfully achieved. It will be seen that the device is of simple construction and of thoroughly dependable action in use and that a 80 high degree of safety and protection is dependably afforded. Moreover, it is to be noted that the device is of simple manipulation and is easily controlled with one hand. It will also be noted that the device is well 85 adapted to meet the varying conditions of hard practical use.

As many possible embodiments may be made of the above invention and as many changes might be made in the embodiment 90 above set forth, it is to be understood that all matter hereinbefore set forth or shown in the accompanying drawing is to be interpreted as illustrative and not in a limiting sense.

I claim:

1. In a device of the character described, in combination, a frame member adapted to be secured to a door and to have a portion thereof extend through an aperture in the door, said frame member having an opening therein with means forming a grating extending thereacross and means for closing said opening, said means including a window-carrying member hinged to said frame and adapted to be locked thereto in closed position, an opaque member hinged to said frame and adapted to overlap said window-carrying member, and spring means acting upon said opaque member and through the latter 105 upon said window-carrying member and operative to tend to swing both of said members about their hinges.

2. In a device of the character described, in combination, a frame member adapted to be secured to a door and to have a portion thereof extend through an aperture in the door, said frame member having an opening therein with means forming a grating extending thereacross and means for closing said 110 opening, said means including a window-carrying member hinged to said frame and adapted to close the opening in the latter, an opaque member hinged to said frame adapted to close the opening in said frame, means 115 for locking one of said members in closed position, and spring means acting yieldingly to hold the other of said members in closed position.

3. In a device of the character described, 120

in combination, a frame member adapted to be secured to a door and to have a portion thereof extend through an aperture in the door, said frame member having an opening 5 therein with means forming a grating extending thereacross and means for closing said opening, said means including a window-carrying member hinged to said frame and adapted to close the opening in the latter, an opaque member hinged to said frame to swing in the same direction as said window-carrying member and adapted to close the opening in said frame, a spring latch 10 construction for locking one of said members in closed position, and spring means operative to move both of said members into closed position.

4. In a device of the character described, in combination, a frame having an annular 20 portion adapted to pass through a round opening in a door and provided with means for securing said annular member to the door, a round frame member carrying a window and adapted to be received within said annular portion, the latter being provided with means projecting inwardly in a radial direction to form with said angular portion an angle into which said frame member may seat itself, an opaque member adapted to cover 25 said window, and means for coaxially hinging both of said members to said frame, said hinging means being constructed and shaped to fall within the outer circumference of said annular portion of the frame.

5. In a device of the character described, in combination, a frame having an annular portion adapted to pass through a round opening in a door and provided with means for securing said annular member to the 40 door, a round frame member carrying a window and adapted to be received within said annular portion, the latter being provided with means projecting inwardly in a radial direction and against which said frame member may seat itself, an opaque member adapted to cover said window, a lug mounted upon said annular portion of the frame, said annular portion being cut away adjacent said lug, a lug on said window-carrying frame 45 member adapted to be received in the cut-away portion of said annular portion of the frame, a hinge pin passing through said two lugs, and means for pivotally mounting said opaque member on said hinge pin.

6. In a device of the character described, in combination, a frame having an annular portion adapted to pass through a round opening in a door and provided with means for securing said annular member to the door, 60 a round frame member carrying a window and dimensioned to be received within said annular portion, the latter being provided with means projecting inwardly in a radial direction to form with said angular portion an angle into which said frame member may

seat itself, an opaque member adapted to cover said window, a pair of spaced lugs on said annular portion of the frame, said annular portion being cut away intermediate of said spaced lugs, means secured to one of said closure members, said means being accommodated in said cut away portion of the annular portion of the frame and being pivotally secured to said lugs, and means mounting the other of said closure members 75 to permit it to be moved into open or closed position relative to the opening in said frame.

7. In a device of the character described, in combination, a frame having an annular portion adapted to pass through a round opening in a door and provided with means for securing said annular member to the door, a round frame member carrying a window and dimensioned to be received within said annular portion, the latter being provided 80 with means projecting inwardly in a radial direction to form with said angular portion an angle into which said frame member may seat itself, an opaque member adapted to cover said window, a pair of spaced lugs on 85 said annular portion of the frame, said portion being cut away intermediate of said lugs, a pair of spaced lugs on one of said closure members and adapted to be received in the cut-away portion of said annular portion of the frame, a pair of spaced lugs on the other of said closure members, and means passing through said lugs for hingedly connecting said two closure members to said frame.

8. In a device of the character described, in combination, a frame having an annular portion adapted to pass through a round opening in a door and provided with means for securing said annular member to the door, a round frame member carrying a window and adapted to be received within said annular portion, the latter being provided with means projecting inwardly in a radial direction and against which said frame member may seat itself, an opaque member adapted to cover said window, a pair of spaced lugs on said annular portion of the frame, said portion being cut away intermediate of said lugs, a pair of spaced lugs on one of said closure members and adapted to be received 100 in the cut-away portion of said annular portion of the frame, a pair of spaced lugs on the other of said closure members, a hinge pin passing through said lugs for hingedly connecting said closure members to said frame, 105 and a spring about said hinge pin and acting upon one of said closure members.

9. In a device of the character described, in combination, a frame having an annular portion adapted to pass through a round opening in a door and provided with means for securing said annular member to the door, a round frame member carrying a window and adapted to be received within said annular portion, the latter being provided with 115

- means projecting inwardly in a radial direction and against which said frame member may seat itself, an opaque member adapted to cover said window, a pair of spaced lugs 5 on said annular portion of the frame, said portion being cut away intermediate of said lugs, a pair of spaced lugs on one of said closure members and adapted to be received in the cut-away portion of said annular portion of the frame, a pair of spaced lugs on 10 the other of said closure members, means passing through said lugs for hingedly connecting said closure members to said frame, means for locking one of said closure members in closed position, and spring means acting upon one of said closure member adapted to swing the latter about said hinge connection.
10. In a device of the character described, 20 in combination, a door having an aperture therein and means on one side of said door for closing said aperture, said means including a window member hingedly mounted to permit it to be swung over or away from said aperture, an opaque member adapted to overlap said window member and hingedly mounted relative thereto, and means urging one of said members and through the latter urging also the other of said members toward aperture-covering position.
11. In a device of the character described, 25 in combination, a door having an aperture therein and means on one side of said door for closing said aperture, said means including a window member hingedly mounted to permit it to be swung over or away from said aperture, an opaque member adapted to overlap said window member and hingedly mounted relative thereto, a handle for said 30 window member, a handle for said opaque member, and spring means urging said opaque member against said window member.
12. In a device of the character described, 35 in combination, a door having an aperture therein and means on one side of said door for closing said aperture, said means including a window member hingedly mounted to permit it to be swung over or away from said aperture, an opaque member adapted to overlap said window member and hingedly mounted relative thereto, means for locking said window member in closed position, and spring means urging said opaque member 40 against said window member.
13. In a device of the character described, 45 in combination, a door having an aperture therein and means on one side of said door for closing said aperture, said means including a window member hingedly mounted to permit it to be swung over or away from said aperture, an opaque member adapted to overlap said window member and hingedly mounted relative thereto, a spring latch for 50 locking said window member in closed position, and spring means for urging both of said members toward aperture-closing position.
14. In a device of the character described, 55 in combination, a door having an aperture therein and means on one side of said door for closing said aperture, said means including a window member hingedly mounted to permit it to be swung over or away from said aperture, an opaque member adapted to overlap said window member and hingedly mounted relative thereto to swing about the same axis as said window member, and spring means acting directly upon one of said members and through the latter upon the other of said members for urging said members toward aperture-closing position.
15. In a device of the character described, 60 in combination, a frame having an annular portion adapted to pass through a round opening in a door and provided with means for securing said annular member to the door, a round frame member carrying a window and adapted to be received within said annular portion, an opaque member adapted to cover said window, means for hinging both of said members to said frame to swing about the same axis, said hinging means being constructed and shaped to fall within the outer circumference of said annular portion of the frame, a manually operable latch for releasably latching said round frame member to said frame, and a manually operable latch member for releasably latching said opaque member to said round frame member, said latching means being constructed and shaped to fall within the outer circumference of said annular portion of the frame.
16. In a device of the character described, 65 in combination, a frame having an annular portion adapted to pass through a round opening in a door and provided with means for securing said annular member to the door, a round frame member carrying a window and adapted to be received within said annular portion, an opaque member adapted to cover said window, means for hinging both of said members to said frame to swing about the same axis, said hinging means being constructed and shaped to fall within the outer circumference of said annular portion of the frame, and latching means for releasably latching said opaque member to said frame, thereby to hold said window-carrying frame member between said frame and said opaque member, said latching means being constructed and shaped to fall within the outer circumference of said annular portion of the frame.
17. In a device of the character described, 70 in combination, a frame member adapted to be secured to a door and having an opening therein with means forming a grating extending thereacross, and means for closing 75
- 80
- 85
- 90
- 95
- 100
- 105
- 110
- 115
- 120
- 125

- said opening, said means including a window-carrying member hinged to said frame, an opaque member hinged to said frame and adapted to overlap said window-carrying member, means for locking said window-carrying member in closed position, and means for locking said opaque member, in closed position, to said first-mentioned locking means.
- 10 18. In a device of the character described, in combination, a frame member adapted to be secured to a door and having an opening therein with means forming a grating extending thereacross, and means for closing said opening, said means including a window-carrying member hinged to said frame, an opaque member hinged to said frame and adapted to overlap said window-carrying member, a spring latch for locking said window-carrying member in closed position, and spring means acting upon said opaque member and through the latter upon said window-carrying member and adapted to swing both of said members into closing position and to effect actuation of said spring latch.
- 15 20 25

In testimony whereof, I have signed my name to this specification this 16th day of March, 1928.

HERMAN HANSEN.
